SPRAY PUMP

Rudolph Bernhardt, Chicago, Ill.

Application April 30, 1936, Serial No. 77,217

2 Claims. (Cl. 103—188)

This invention relates particularly to improvements in the details of construction of small pumps or sprayers such as commonly used for spraying liquids from bottles or containers. 5 Among the objects of this invention are to provide an improved pump or sprayer which can be made at a very low cost and which will be efficient and durable in operation; to provide an improved cylinder for spray pumps drawn or formed from 10 a single piece of sheet metal; to provide an improved piston; and to provide such other advantages and improvements as will appear from the following description.

In the accompanying drawing illustrating 15 this invention,

Figure 1 is a side view of a bottle or container with my improved pump mounted therein;

Figure 2 is an enlarged sectional view of the cylinder and piston;

Figure 3 is a perspective view of the cylinder;

Figure 4 is a perspective view of the piston and a portion of the piston rod; and

Figure 5 is a sectional detail of the lower end 20 of the cylinder taken at approximately right angles to Figure 2.

As shown in the drawing, 6 represents a bottle or container having my improved pump or sprayer mounted therein. The pump has a cylinder 7 which is adapted to rest on the bottom 25 of the bottle as shown in Figure 1, in order to support the same against the downward thrust of the piston. Heretofore cylinders of this kind have usually been made of two or more pieces, tubing being frequently used with a washer or 30 head secured in the end thereof for the valve seat. In accordance with this invention I draw or form the cylinder from a single piece of metal, preferably sheet metal, to provide the main tubular portion 7 and an integrally formed head and 35 valve seat 8. The head has a downwardly extending annular bead or edge 9 which engages with the bottom of the bottle and has an upwardly or inwardly extending annular rib 10 with a groove 11 therebetween. The annular rib 10 defines an inlet opening or hole 12 and also provides a seat for the ball valve 13. A plurality of radial 40 grooves or indentations 14 are provided around the lower end or through the annular bead 9 to permit free passage of liquid from the bottle to the hole 12. My improved cylinder may be readily drawn from suitable sheet metal with all of the parts thus described formed therein, thus facilitating the rapidity of manufacture as well as reducing the cost of the same and providing a

unitary structure having no parts to become loosened or get out of order.

A U-shaped ball retainer 15 is placed over the ball 13 and has outwardly extending feet or projections 16 which are engaged by the spring 17 for holding the retainer in position.

The upper end of the spring 17 engages with a disc or washer 18 having an outlet hole or valve seat 19 which is engaged by a ball valve 20 in the form shown, although in some instances this valve may be omitted, particularly where the discharge is provided with a small aperture.

The disc 18 engages with the lower end of the piston 21 which is also preferably formed of a single piece of suitable material such as sheet 15 metal and which fits closely within the inner bore of the cylinder 7. The upper end of the piston is reduced to form a bearing or neck 22 which receives the lower end of the hollow piston rod or discharge pipe 23 which is preferably secured 20 thereto by means of a driving fit or frictional engagement. The piston is held in operative position in the cylinder by projections 24 formed by indenting the cylinder adjacent to the upper end thereof.

The discharge pipe 23 extends up through the cap of the bottle and is provided with any suitable spray nozzle or the like 25 and with a thumb-piece 26 for reciprocating the same to actuate the sprayer.

It will also be noted that the drawing or forming of the piston out of a single piece of sheet metal or the like tends to reduce the cost of the same and the provision of the neck portion 22 which is secured directly to the end of the hollow 35 rod or pipe 23 permits the use of shorter rods or tubing and thus reduces the cost of the complete pump.

Having thus described my invention what I claim is:

1. In a spray pump, the combination of a cylinder formed of sheet metal having an integrally formed closed end adapted to rest upon the bottom of a receptacle from which liquid is to be pumped, said end extending upwardly into the cylinder and having an inlet opening therein, radial passageways around the end, a valve engaging with said opening, a valve retainer over said valve, a spring engaging with said retainer, a washer engaging with the opposite end of the spring, a tubular piston formed of sheet metal fitting closely within the cylinder and having its lower end engaging with said washer, projections at the top of the cylinder for holding the piston in engagement with the cylinder, said piston hav-

ing a reduced tubular upper end, a hollow piston rod having its lower end fixed in said reduced upper end, and a discharge nozzle for said rod.

2. In a spray pump, the combination of a cylinder formed of sheet metal having an integrally formed closed end adapted to rest upon the bottom of a receptacle from which the liquid is to be pumped, said end extending upwardly into the cylinder and then downwardly, defining an inlet opening and forming a tapered valve seat, inlet passageways around the end, a valve engaging with said opening, a valve retainer over said valve, a spring engaging with said retainer, a

washer engaging with the opposite end of the spring and having an opening provided with a valve seat therein, a valve coacting with said valve seat, a tubular piston formed of sheet metal fitting closely within the cylinder and having its lower end engaging with said washer, integrally formed means at the top of the cylinder for holding the piston in engagement with the cylinder, said piston having a reduced tubular upper end, a hollow piston rod having its lower end fixed in said reduced upper end and having a discharge at its upper end.

RUDOLPH BERNHARDT.
